FILM REEL CONSTRUCTION

Philip L. Karr, Chicago, Ill., assignor to Excel
Movie Products, Inc., Chicago, Ill., a corpora-
tion of Illinois

Application March 29, 1946, Serial No. 658,071

8 Claims. (Cl. 242—74)

1

This invention relates to spools or reels and more particularly to reels for moving picture film.

One of the objects of my invention is the provision of a reel for film in which the film may be very readily secured for winding and from which the film is readily removable without injury thereto.

Another object of this invention is the provision of a reel of the character set forth, which is simple in construction and inexpensive to manufacture.

Other and further objects of the present invention will be apparent from the following description and claims and are illustrated in the accompanying drawing which, by way of illustration, shows a preferred embodiment and the principle thereof. Other embodiments of the invention embodying the same or equivalent principle may be used and structural changes may be made as desired by those skilled in the art without departing from the present invention and a purview of the appended claims.

In the drawing:

Fig. 1 is a front elevational view of a reel embodying my invention.

Fig. 2 is a sectional view taken on line 2—2 of Fig. 1.

Fig. 3 is an enlarged sectional view taken on line 3—3 of Fig. 1.

Fig. 4 is an enlarged sectional view taken on line 4—4 of Fig. 1.

Referring to the drawing, the reel illustrated comprises two identical companion sheet metal stampings, indicated generally by the numerals 7 and 7', and formed to provide flanges 8 and 8', each having a hub portion 10 and 10'. Since the companion stampings are identical in construction only one will be described, with primed reference numbers used to identify corresponding parts of the companion stamping.

In the preferred embodiment of my invention, openings 12 are stamped out of each flange to reduce weight without impairing the rigidity. Each stamping is formed with an opening 13 for receiving a spindle. Two lugs 14 and 15 are struck out of the flange 8 and are bent out of the plane of the flanges at right angles thereto to support the film when the latter is wound thereon, and provide a portion of the hub structure. Projections 16—16 are provided at the ends of the lugs 14 and 15 and are adapted to be received in registering apertures provided in the companion stamping. The projections 16 are arranged to be peened over to secure the stamp-

2

ings 7 and 7' in assembled relation. As will be noted, the two lugs 14 and 15 and apertures 17 and 18 in the stamping 7 are spaced radially about 90° apart, the lugs 14 and 15 being located in one half of the hub circle and the apertures 17 and 18 in the other half. Two semi-circular tabs 20 and 21, arranged on a diametrical line and struck from the stamping 7, are bent at right angles to the plane of the flange 8 and, when in juxtaposed relation to corresponding tabs such as 21', illustrated in Fig. 2, of the companion stamping 7', are arranged to provide additional platform surfaces to support the wound film.

15 Two tabs 23 and 24, arranged on a diametrical line, are struck out of the hub portion of the stamping 7 and are bent out of the plane of the flange 8 to provide platform portions 26 and 27 and lips 29 and 30, respectively, with the lips 10 lying in a plane parallel to that of the flange, and offset therefrom. Companion lips 29, 30', and 30, 29' of companion stampings 7 and 7' are arranged in juxtaposition with the lips in spaced relation.

20 The side flange 8 is provided with a radial slot 32 which extends from the marginal edge of the flange 8 to the hub portion 10 and through the platform portion 27 to the lip 30. The slot 32 connects with a slot 34 provided in the lip 30.

25 As viewed in Fig. 1, the slot 34 is slightly inclined upwardly with respect to the longitudinal axis of the slot 32. Another slot 35 is provided in the platform portion 26 of the opposite tab 23 and connects with a slot 37 in the lip 29, said slot being inclined downwardly, as viewed in Fig. 1.

30 As was previously noted, each of the stampings 7 and 7' is identical in construction, but in assembly the stampings are turned 180° relative to each other so that companion lips 29 and 30' 40 and 30 and 29' are juxtaposed and are in spaced relation, as shown in Fig. 2. The slot of the platform portion 26' is in alignment, however, with the slot 32. The slots 34 and 37' of juxtaposed lips 30 and 29', respectively, are oppositely inclined and as will be presently described, operate to retain a film end 40 therebetween.

35 Preliminary to winding a film on the reel, the film end is grasped between the fingers at a distance substantially equal to the length of the slot 32 and is inserted sidewise therethrough to position the film within the plane of the side flanges 8 and 8'. The film end is then urged towards the center of the reel to cause the terminal portion of the film to enter between the oppositely inclined slots 34 and 37' and to be deformed there-

by across the width of the film into a substantially ogee configuration, as shown in broken lines in Fig. 4, so as to thereby afford increased friction to prevent withdrawal of the film during the initial stages of the winding operation. 5 The inherent resilience of the film urges the film against the sides of the slots 34 and 37', thereby causing the film to be retained with sufficient firmness for winding, but yet sufficiently yieldable to permit removal of the film from the reel 10 without injury to the film.

It will be seen from the foregoing that an effective securement of the film end for winding on the reel is accomplished in a minimum amount of time, and with a minimum of effort. In view 15 of the provision of duplicate structure on each side flange stamping, a slot is conveniently available to the user for beginning the winding of the film regardless of which side is presented to view when the reel is picked up for use.

I claim:

1. A device of the character described comprising two flanges and a hub portion, means in said hub portion for receiving a film end therein and retaining the same, said means including a pair of juxtaposed lips in spaced relation, each of said lips having a slot for receiving a film end, the slots being so arranged that the film end when received therein is deformed substantially in an ogee configuration.

2. A device of the character described comprising two flanges and a hub portion, said hub portion having two slots for receiving a film end therein, said slots being disposed in spaced parallel planes and angularly inclined relative to each other and arranged when a film end is received therein to deform the same substantially in ogee configuration.

3. A device of the character described comprising two flanges and a hub portion, means in said hub portion for receiving a film end, said means including a pair of juxtaposed lips in spaced relation, a slot in each of said lips, the said slots being oppositely inclined relative to each other, a slot in one of said flanges extending between the hub and the periphery of said flange and connected to one of said first mentioned slots in one of said lips, said slots arranged for receiving a film end sidewise and for deforming the terminal portion thereof in substantially ogee configuration across the width of the film to retain the film end securely for winding.

4. A device of the character described comprising two flanges and a hub portion, each of said flanges having a lip in the hub portion with the lips arranged in juxtaposition, each of said lips having a slot with the slot of one lip out of registering alignment with the other, one of said flanges having a slot extending from the periphery and connected with one of said first mentioned slots, said slots arranged to receive a film end sidewise and to deform the terminal portion of said film end substantially in ogee configuration to retain the same firmly for winding the film on the reel.

5. A device of character described comprising a pair of substantially identical members each having a flange and a hub portion, a lip formed out of each of said hub portions, said lips disposed in planes parallel to said flanges and arranged in juxtaposition, each of said lips having

a slot with the slot of one lip slightly out of registering alignment with the other, one of said flanges having a radial slot extending from the periphery thereof and connecting with one of said first mentioned slots, said slots arranged to receive a film end sidewise and to deform the terminal portion of said film end substantially in ogee configuration to retain the same firmly for winding the film on the reel.

6. A film reel comprising a pair of substantially identical members, each having a flange and a hub portion, complementary tab members associated with the hub portion and extending inwardly with the ends thereof juxtaposed, said tabs having curved slots which together form a substantially ogee curve, one of said flanges having a radial slot extending from the hub portion to the marginal edge thereof and connecting with one of said first mentioned slots to receive a film laterally, said film when received in said slots being deformed substantially in an ogee curve and thereby secured for winding on said reel.

7. A film reel comprising two flanges and a hub portion therebetween, said hub portion having a radially directed slot extending inwardly thereof between said flanges in a plane at right angles to said flanges, said slot having portions disposed out of the plane thereof and arranged when a film end is received in said slot to deform said film end out of its normal plane across the width of the film thereby to releasably secure the film for winding on said reel.

8. A film reel comprising two flanges and a hub portion therebetween, said hub portion having a radially directed slot extending inwardly of said hub portion between said flanges in a plane at right angles to said flanges, one of said flanges having a radial slot extending from the hub portion to the periphery thereof and arranged to receive a film end sidewise, said slot being disposed in the same plane as said first mentioned slot and connecting therewith, said first mentioned slot having portions disposed out of the plane thereof and arranged when a film end is received therein to deform said film end out of its normal plane across the width of the film thereby to releasably secure the film for winding on said reel.
